COMBINATION FURNACE, FIREPLACE, BROILER
Joseph Michael Agnese, 2770 Greenwich St.,
San Francisco, Calif.
Filed Mar. 13, 1963, Ser. No. 264,842
10 Claims. (Cl. 126—6)

This invention relates generally to a room or house heater, and has for one of its objects the provision of a combination furnace, fireplace, broiler and rotisserie.

Another object of the invention is the provision of a combination fireplace and furnace that may be selectively used or in combination, and that is highly efficient when selectively used or in combination.

An additional object of the invention is the provision of a fireplace that may be readily installed in houses already built, and that is adapted to provide more efficient heating than heretofore.

An added object of the invention is the provision of a combination fireplace, broiler and furnace that is economical to make and to install, and which combination includes means providing a convenient work table around the broiler and other structure that facilitates keeping it clean.

Other objects and advantages will appear in the description and in the drawings, in which:

FIG. 1 is a perspective view of the combination, certain parts being broken away to show interior structure.

FIG. 2 is a vertical sectional view taken through the heater of FIG. 1 certain parts being shown in elevation and in broken lines.

FIG. 3 is a slightly reduced, cross sectional view taken along line 3—3 of FIG. 2.

FIG. 4 is a cross sectional view taken along line 4—4 of FIG. 2.

FIG. 5 is a reduced size perspective view of a work table adapted to be supported on the heater.

FIG. 6 is a slightly modified view of the cap or uppermost portion illustrating one modification where hot air is to be conducted from the heater to different parts of the house.

In the description and claims the invention will be generally called a heater, inasmuch as it performs that function whether used as a fireplace, broiler, rotisserie or furnace, or any combination thereof.

The wall of a room or building against which the heater is adapted to be installed is generally designated 1, the floor is designated 2, and the ceiling 3 (FIG. 2). The specific structure of these is immaterial, except that the wall 1 may be the wall on one side of the studding and the space behind the wall or on the side of wall 1 opposite to the heater, may be the wall of another room, in which case, the vertical vent flue, designated 4, will be between the walls or within the partition.

A vertical plate 5 is secured against wall 1, which plate may include conventional fire insulation between it and the wall, although the said plate merely functions as one wall of a hot air flue, or conduit. The hot air flue or conduit having the plate 5 as one of the walls thereof may extend from the floor 2 substantially to the ceiling 3, and secured in spaced opposed relation to the face of said plate that faces into the room is a second vertical plate 6 having relatively narrow vertical sidewalls or plates 7, that are along its side edges and that extend to the plate 6.

The plates 5, 6 and plates 7 are coterminous at a point spaced below the ceiling so that a horizontal cap 8 having depending flanges 9 along two of its opposite edges may be secured over the upper edges of plates 5, 6 with the flanges 9 extending over the oppositely outwardly facing surfaces of said plates. However, the uppermost portion of plate 6 is cut away to form a horizontally elongated opening 10 below the adjacent flange 9 (FIG. 1). These

plates 5, 6, 7 coact to define the walls of a vertical passageway 13, having a laterally directed outlet at the upper end thereof opening into the room.

The lower end of the plates 6, 7 that form the forward and lateral sides of the passageway 13 terminate at different distances from the floor, the plates 6 terminating at 14 (FIG. 2) a substantial distance above the lower terminating end of the plate 5, and at a substantial distance below the level at which the side plates or walls 7 terminate. In planes parallel with walls 7, but equally spaced inwardly from the side edges of the front plate 6, and consequently from plates 7, are a pair of spaced opposed walls 16 that extend downwardly from the point 14 at which side plates 7 terminate to the floor, and which walls 16 extend forwardly, or in a direction away from the front plate 6 at right angles to the latter. These walls 16 are integral with a forward wall 17 that is of the same height as walls 16 and that also extends to base plate 18.

20 The base plate 18 extends to and joins the wall plate 5 along the rear edge of plate 18, and is formed with lateral opposed sidewalls 19 and a front wall 20, that extend to the floor 2. The front wall 20 is formed with a horizontally extending opening 23 (FIG. 1).

25 From the foregoing description it will be seen that from the point 14 where the lower edges of the side plates 7 terminate to the point where the lower edge of the front plate 6 terminates, a horizontally disposed, rectangular sheet metal frame is formed by the lower portion of plate 6 and walls 16, 17, the forward wall 17 being opposed to the front wall 6 of the passageway 13. Also it is seen that below this rectangular frame the walls 16, 17 continue to the base plate 18, and the rear edges of the walls 16 are spaced from the wall plate 5, thus providing laterally directed openings 24 between the rear edges of the walls 16 and the wall plate 5, through which openings room air may pass freely into the lower end of passageway 13 for passage up the latter and back into the room through outlet 10.

30 40 An imperforate, horizontal plate 25 (FIGS. 1, 2) closes the lower end of the rectangular frame formed by walls 16, 17 and the lower portion of the front plate 6.

Spaced below the plate 25 and spaced from the walls 16 and 17 is the firebox, generally designated 26, which 45 firebox has an imperforate top wall 27 spaced below and parallel with plate 25; a pair of imperforate, parallel sidewalls 28, an imperforate front wall 29 and an imperforate rear wall 30. Said sidewalls, front wall and rear wall of the firebox extend to the base plate 18, and the area enclosed by said walls is formed with air inlet openings 32 (FIG. 2).

50 55 A conventional burner 34 is positioned within the firebox 26, which burner may be connected by a pipe 35 that is connected with a source of fuel. This pipe 35 preferably extends through the rear wall 30 and may have a valve 36 that is accessible through either of the side openings 24. One or more vents 37 communicate between the upper portion of the firebox and the vent flue 4 and extend across the space between the rear wall 30 60 of the firebox and the wall plate 5, hence are in heat exchange relation to air entering the openings 24 and passing up passageway 13.

65 It may be noted that in the present installation branch pipes 38 from the vent flue 4 project laterally to the surface of wall 1 and may extend into preformed openings in the wall plate 5. The vent pipes 37 telescopically extend into said branch pipes 38. Thus the heater as a whole is readily connected with the vent flue 4 in installing it.

70 The forward wall 17 of the lower rectangular frame portion of the heater is formed with an opening 39 through which room air may enter the space 40 between the top

of the firebox and the bottom frame plate 25 for passage to the lower end of the passageway 13.

The lower portion of the forward wall 17 extends across and spaced from the forward wall 29 of the firebox, and this wall may be formed with an opening closed by a door 43, which in turn, may be formed with openings 44 that may be opened and closed to any designed degree by a conventional sliding damper manually actuatable by grasping a knob or handle 45 and moving it to the degree desired for sliding the damper to open or closed position.

Air that may be admitted through the opening 44 will, of course, be free to pass over the front and upper sides of the firebox on the way to passageway 13, and to thus be heated to the desired degree for ejection into the room through outlet 10.

The description up to this point is that of the furnace, and it is obvious that the opening 10 may be damper controlled, as is indicated by the damper 46 (FIG. 6) which may be incorporated in the wall 47 of the cap 48 instead of using a cap such as is indicated in FIGS. 1, 2. Also, the plates 5, 6 and 7 may be proportioned and formed to carry conduit connections or outlets 49 that are adapted to connect with air conduits leading to different rooms in a house, each of which may be controlled by a damper 50.

The portion of the heater above the wall 25 carries the fireplace and broiler features, including the rotisserie.

Slidable on wall 25 or, if desired, on any suitable runners on said wall, is an ashpan 53 that may be guided between guides 54 for sliding into and out of the rectangular frame portion of the heater through a horizontally elongated opening in the forward wall 17. The front side 55 of the ashpan will close said opening and the rear wall 56 of the pan will be against the plate 6 when said ashpan is fully within said frame portion. Upon partially drawing the ashpan outwardly the ashpan opening in the forward plate 17 will be partially opened to assist in providing a draft for the fuel that is supported above the pan. A hand grasping projection 57 on the front side 55 of the ashpan is provided for manually withdrawing the pan.

Inwardly projecting members 58 secured against the walls 6, 18 above the ashpan are adapted to support the fuel grate 59 thereon. This grate is provided with imperforate marginal portions 60 (FIG. 3) and any suitable means, such as bars 63 are adapted to support the fuel thereon, such as wood or charcoal. The marginal portion that is over the rear wall 56 of the ashpan is sufficiently wide to prevent ashes from falling between wall 56 and the wall 6 when the ashpan is partially withdrawn, as has been described above.

This grate is the fireplace grate and it also functions as the grate for the broiler and carries a vertical central post 64 that is threaded at its upper end portion for the threaded central part of an annular grill 65 on which meat or other food may be broiled or cooked. The grill 65 is rotated to elevate or to lower it, and it is removed when the heater is used as a fireplace.

One of the sidewalls 16 carries a conventional rotisserie motor 66 provided with a chuck to receive one end of a spit, while the opposite wall is recessed to rotatably support the other end of the spit. Obviously, the spit may be rotatably supported at opposite ends by walls 16 and manually rotated, if a motor driven spit is not desired. The spit, and the manner of supporting and driving it, are all conventional in barbecue broilers.

A horizontally disposed, generally U-shaped frame 68 (FIGS. 1, 5), the legs and connecting end portion of which are flat and coplanar, is adapted to be supported horizontally on the upper edges of sidewalls 16 and front wall 17 and to project outwardly therefrom to provide a work table around the broiler. The outer edges of this frame are bent to provide a flange 69 (FIG. 2) or said outer edges may be rolled, if desired, to avoid laterally directed sharp edges. When in position, the rear edges of the legs of the U-shaped table 68 are against the front side or plate 6 of passageway 13, and legs (FIG. 5) may be stamped down-

ward from the table as at 70 to engage the inner sides of walls 16 adjacent to the forward wall 17 to properly position the table on said walls and to hold it against accidental dislodgement laterally.

A horizontally disposed U-shaped screen 73 of screening or perforated metal may be removably supported on its edge on the table 68, with the end edges of the legs of the screen against the plate 6 (FIG. 1) when the heater is used as a fireplace, or at any time when there may be danger from sparks.

A hood generally designated 74 is adapted to be suspended from the lower edge of the outlet opening 10 to rest against the wall or plate 6. This hood has a pair of corresponding triangular opposed sidewalls 75, one of the free edges of which are vertical and against said plate 6. A hood or canopy plate 76 integrally connects walls 75 along the edges of said walls that extend slantingly downwardly and outwardly relative to plate 6, and said hood plate has a reversely bent extension 77 (FIG. 2) along its horizontal upper edge that is adapted to extend through opening 10 and downwardly inside passageway 13 to function as a hook for suspending the hood from said plate 6.

The remaining two edges of the sidewalls or plates 75 of the hood extend slantingly rearwardly and downwardly from the ends of the lower edge of the hood plate 76 to the plate 6 at points adjacent to but spaced above the table or platform 68. The ends of screen 73 are adapted to extend between the lowermost ends of side plates or walls 75.

In operation as a furnace, when the burner within firebox 26 is in operation, the cold room air is adapted to pass around the firebox in heat transfer relation to the latter, entering through the openings 44 in door 43 and through inlet 39 and will pass up the passageway 13 and out of outlet 10 into the room. Room air from opposite sides of the heater is free to enter the lateral openings 24 that are at the rear of the firebox, and this air will be entrained with the air that has entered through openings 39, 44.

The outlet 10 and inlet openings 44 may, as already indicated, be damper controlled, and when air ducts or conduits 49 are connected with the upper end of passageway 13, these may be damper controlled, as indicated, to divert the air to different rooms, as desired, or to close them so the air will be discharged into the room in which the heater is positioned.

When the heater is used as a fireplace, the fuel will be burned on grate 59, and the wall 6 will receive heat from the fireplace fuel and wall 25 of the air duct 49 will also receive heat, therefore, room air will be induced to flow through passageway 13 in heat transfer relation to said walls, and into the room. Furthermore, plate 76 will be heated from the burning material in the fireplace and this heat will be dissipated into the room to heat the air therein. The same heating of room air will occur when the heater is used as a broiler.

In its broadest aspect, from a structural standpoint, a vertically extending air passageway is provided, having lateral walls with relatively high heat conducting properties, such as metal, and these walls, such as walls 6, 7, are adapted to project into the room so as to be in direct heat transfer relation to the room air. An air inlet is at the lower end of the passageway to admit room air into the latter, and an outlet is at the upper end to discharge the air into the room. Preferably the inlet is adjacent to the floor of the room and the outlet adjacent to the ceiling.

A shell or housing formed by lateral walls 16, 17 that is open at its upper end is offset to one side of the vertically extending passageway, and a horizontal wall 25 divides this shell or housing into an upper fireplace and broiler section and into a lower firebox section with a horizontal passageway between them communicating with room air at one end and with said vertically extending passageway at the other end.

A bottom wall closes the lower end of the fireplace

and broiler section and also defines the upper wall of the said horizontally extending passageway for room air, while the lower side of the passageway is the upper wall of the firebox section and is heated by fire in said firebox. The other walls of the horizontally extending passageway are two of the lateral walls 16 of the shell or housing.

Two opposite air inlets at two of the opposite sides of the lower end of said vertical passageway admit air directly from the room to the lower end of the vertically extending passageway at about the point where the horizontally extending passageway opens into the lower end of said vertically extending passageway for entrainment with air heated in passing through the horizontally extending passageway. The hood 74 over the shell gets heat from within the housing or shell since it is offset to the same side as the shell, and one sidewall of the vertical passageway 13 closes one side of the hood.

It should also be noted that the products of combustion from both the firebox and the fireplace and broiler section are enclosed in pipes or flues that cross the passageway through which the room air passes, hence, the air extracts or picks up heat from these flues.

This is the basic structure. The ashpan, grill and rotisserie, are additions and parts of the fireplace or broiler section.

It is to be understood that the entire unit, including the wall plate 5, is portable, the same as an electrical refrigerator, and other appliances. The vent flue 4 may be spaced within the passageway 13 and connected with 30 a chimney flue or the like in the same manner as a stovepipe, and one or more conventional thermostatically actuated draft inducing electric fans may be positioned in the rear of the firebox upon the air around the firebox being heated by commencement of the burner. These 35 are conventional features in connection with furnaces and the like, and are well known to those skilled in the art.

Although the invention has been described and illustrated in detail, it is obvious that modifications may be 40 made therein within the scope of the annexed claims without departing from the spirit of the invention.

I claim:

1. A heater adapted to provide a furnace and a fireplace within a room in a house, comprising:
 (a) a vertically extending passageway having an inlet 45 for room air adjacent to its lower end and an outlet for said air at its upper end;
 (b) a housing of sheet metal extending forwardly from said passageway having lateral sidewalls, front and rear walls, and an open top; 50
 (c) a horizontal, imperforate wall within said housing intermediate the open top and lower end thereof extending to said lateral sidewalls and front and rear walls dividing it into an upper fireplace and broiler section and a lower firebox section; 55
 (d) a firebox in said firebox section having heating means therein and also having an imperforate top wall spaced below said horizontal wall to provide a passageway for air between them;
 (e) said front wall of said housing being formed with 60 an opening at a point remote from said inlet, communicating with said last mentioned passageway for admitting room air to said last mentioned passageway, said last mentioned passageway terminating at one end thereof adjacent to said inlet and communicating with said inlet at said one end for passage of air from said last mentioned opening across said top wall to said lower end of said vertically extending passageway. 70

2. In a heater as defined in claim 1:

(f) a grate within said fireplace section of said housing on which fuel is adapted to be burned;
 (g) a hood spaced above the upper open end of said housing opening downwardly for receiving therein 75

heat and the products of combustion from said fireplace section;

(h) at least one metal flue opening at one end to within the upper portion of said hood and extending across said vertically extending passageway for passage of air in said vertically extending passageway past said flue in heat exchange relation thereto.

3. In a heater as defined in claim 2:

(i) a discharge flue extending from said firebox across said inlet for passage of room air thereover and into said vertically extending passageway in heat transfer relation to said discharge flue.

4. A heater adapted to provide a furnace and a fireplace and broiler, comprising:

(a) housing having lateral sidewalls, a front wall and a rear wall, and an open top;

(b) a pair of horizontally disposed, vertically spaced plates within said housing intermediate its upper and lower ends defining opposite walls of a horizontally extending passageway for air between said spaced plates and dividing said housing into a fireplace and broiler section above the upper of said pair of plates and a firebox below the lower of said pair of plates;

(c) said front wall of said housing being formed with an opening for admitting room air to said passageway and an outlet in the back of said housing opposite to said opening for discharge of air from said passageway;

(d) a vertically extending passageway at one side of said housing having an inlet at its lower end in communication with said outlet, and a discharge opening at its upper end for discharge of air therein back into the room in which said heater is adapted to be positioned;

(e) a base plate on which said housing is supported including means for supporting said base plate and housing elevated above a floor;

(f) said base plate being formed with openings for admission of air into said firebox, and a discharge flue at the upper end of said firebox for discharge of products of combustion therefrom;

(g) a horizontal grate within said fireplace and broiler section;

(h) means carried by said housing removably supporting said grate spaced above the upper plate of said pair;

(i) a horizontally disposed ashpan slidably supported between said upper plate of said pair and said grate for removal from one of the sides of said housing and an opening formed in said one of said sides through which said ashpan is removable;

(j) said grate including a horizontally disposed imperforate marginal portion extending over said ashpan along the portion of said pan that is opposite to said last mentioned opening to prevent ashes on said grate from falling behind said pan when the latter is partially drawn out of said opening to admit draft air to said grate.

5. In a heater as defined in claim 4:

(j) a vertical post on said grate extending upwardly therefrom and threaded at its upper end;

(k) a horizontal grill threadedly supported by the threads on said post for supporting food to be cooked at different distances above said grill.

6. In a heater as defined in claim 5:

(l) a hood suspended from one of the walls of said vertically extending passageway in a position over the open top of said housing for receiving the products of combustion from burning material on said grate and for receiving the fumes from food on said grill.

7. A heater adapted to provide a furnace and fireplace within a room, comprising:

(a) a vertically extending passageway for air having walls of heat transfer material adapted to be in direct heat transfer relation with the air in said room;

- (b) a firebox at the lower end of said passageway extending forwardly from one side thereof, and having heating means therein;
  - (c) a horizontal extending passageway for air extending across the top of said firebox in communication with the lower end of said vertically extending passageway at one of its ends and in communication with outside room air at its opposite end;
  - (d) laterally oppositely outwardly opening inlets at the lower end of said vertically extending passageway in communication with the lower end of the latter adjacent to the point at which said horizontally extending passageway is in communication with said vertically extending passageway for admitting air into the lower end of said vertically extending passageway for entrainment with heated air from said horizontally extending passageway.
8. In a heater as defined in claim 7:
- (e) an outlet at the upper end of said passageway adapted to open directly into the room in which said heater is adapted to be positioned.
9. In a heater as defined in claim 8:
- (f) a horizontally disposed fireplace grate above said horizontally disposed passageway adapted to support fuel to be burned therein;
  - (g) lateral, vertically disposed sheet metal walls including one of the walls of said vertically extending passageway enclosing said grate whereby said one of the walls of said passageway will be heated by such fuel;
  - (h) sheet metal walls spaced above said grate defining the sides of a generally vertically extending passageway for the products of combustion from said fuel on said grate, one of which walls is one of the walls of said vertically extending passageway.
10. In a room having a sidewall and a vertically extending flue thereon for conducting away the products of combustion:
- (a) an upper and a lower branch conduit vertically spaced apart and communicating with the interior of said flue at one of their ends and opening into said room at their opposite ends at points approximately even with the inner surface of said wall that faces into said room;
  - (b) a vertically elongated metal wall plate secured against said inner surface formed with openings in registration with said opposite ends of said branch conduits;
  - (c) a combination furnace, fireplace and broiler within said room that includes a housing having a vertical rear wall and vertical sidewalls, an open top and a horizontal plate within said housing intermediate its upper and lower ends dividing said housing into an upper fireplace section above said horizontal plate and a firebox section below said horizontal plate;
  - (d) a vertically disposed front plate in spaced opposed

- and parallel relation to said wall plate extending upwardly from said housing with said rear wall being a downward continuation of said front plate;
- (e) opposed side plates along two opposite edges of said vertically disposed front plate and integral with the latter extending to said wall plate whereby said wall plate, vertically disposed front plate and said side plates define a vertically extending passageway;
- (f) said firebox section including a firebox having heating means therein;
- (g) a discharge flue connected with and projecting from said firebox into the lower of said branch conduits for conducting the products of combustion from said firebox into said vertically extending flue;
- (h) a closure over the upper end of said vertically extending passageway;
- (i) an outlet formed in said vertically disposed front plate adjacent to its upper end having a lower edge, said outlet opening into said room;
- (j) a hood having three adjoining walls one wall thereof extending slantingly outwardly and downwardly from said lower edge of said outlet and the other two walls being in spaced opposed relation extending to said vertically disposed front plate;
- (k) means on said one wall extending over said lower edge of said outlet suspending said hood from said edge in a position extending over the open top of said housing;
- (l) a horizontally disposed discharge flue extending into said upper of said branch conduits at one end thereof and opening at its opposite end into the space between said one wall of said hood and said front plate for conducting the products of combustion and fumes from within said hood to said vertically extending flue;
- (m) a grate supported within said fireplace section spaced above said horizontal plate for supporting fuel to be burned therein; and,
- (n) a horizontally disposed air passageway between said firebox and said horizontal plate communicating at one end thereof with said vertically extending passageway and communicating at its opposite end with the room air for conducting room air to said vertically extending passageway along a path below said grate and above said firebox.
